MONEY BOX

Filed Oct. 24, 1922

INVENTOR;

John Edgarley Purser
By Otto Henck
his Attorney

UNITED STATES PATENT OFFICE.

JOSEPH EDGERLEY PURSER, OF BRISTOL, ENGLAND.

MONEY BOX.

Application filed October 24, 1922. Serial No. 596,543.

To all whom it may concern:

Be it known that I, JOSEPH EDGERLEY PURSER, residing at Fishponds, Bristol, in the county of Gloucester, England, a subject 5 of the King of Great Britain and Ireland, have invented certain new and useful Improvements in Money Boxes, of which the following is a specification.

This invention relates to money boxes and 10 especially to boxes known as home safes.

This invention refers to that type of money box wherein the inserted coin is received by a rotary coin-carrier and transferred to an aperture in a subjacent fixed 15 plate whence it falls into the box.

The object of the invention is to provide a money box of simple and compact construction in which coins of any denomination and to any value may be inserted within 20 the limits of the coin aperture or apertures and the capacity of the box, and one to which access may be obtained at any time by an authorized person.

A box made in accordance with this invention is fitted with a revoluble disc constituting a coin carrier, perforated in one or more places to receive coins, an aperture in the top of the box adapted to register with the hole or one hole at a time in the disc, a fixed plate within the box adapted to close the inner face of the hole or holes in the revoluble disc, the revoluble disc being provided with a groove on its inner face, and the top of the box behind which the disc 30 revolves being furnished with a corresponding groove or recess, the groove in the disc lying in or under the groove in the top of the box, one or more fingers being associated with the fixed plate so as to lie 35 in the groove in the disc and extending towards the outer surface of the box beyond the outer face of a coin placed in the coin hole.

The disc is provided with an actuating 45 device such as a handle operable from the exterior of the box, or the disc may have a milled edge and the box a gap through which the milled edge may be actuated. The disc is furnished with means to prevent it being turned in more than one direction.

One side of the box is hinged, or detachably connected, and secured by a lock in any suitable manner.

Referring to the drawings filed here- 55 with:

Fig. 1 is a plan of one form of money box made in accordance with this invention;

Fig. 2 is a section on line A—A, Fig. 1; 60

Fig. 3 is a plan of the revoluble disc;

Fig. 4 is a part plan of the bottom of the box; and

Fig. 5 is a section on line B—B, Figs. 2 65 and 4.

The box *a* is oval in shape. The top *b* of the box *a* is provided with an annular projection *c* and a corresponding recess and is perforated with a coin aperture *d*. Within the box *a* is pivotally mounted a revoluble 70 disc *e* having three coin apertures *f*, *f*, *f*, large enough to receive the biggest coin which is to be placed in the box. The disc *e* is thick enough to accommodate the thickest coin in use, or it may be flanged for 75 the same purpose. The disc *e* is provided with an annular flange or embossment *g* and recess *h*; this flange *g* extends across the holes *f*, *f*, *f*, and forms a complete ring. Under the disc *e* is a plate *j* fixed to the 80 sides of the box and formed with a hole *k* staggered with respect to the coin aperture or hole *d* in the top of the box *a*. This plate *j* supports a coin inserted in the holes *d* and *f* when these are in register with one 85 another. A finger *m* is furnished on the fixed plate *j* so as to lie in the groove or recess *h* of the disc *e* and it projects into the groove so that its point lies above the upper face of the coin when reposing there- 90 in. The projection *g* on the disc *e* lies in the recess formed by the projection *c* in the top *b* of the box *a*. A roller *n* is situated in the space between the disc *e* and the side of the box *a* and a spring *o* likewise so as 95 to press the roller against both the disc and the side of the box.

The disc *e* is provided with a handle *p* which lies below the face of the projection *c* in the top *b* of the box *a*. Below the fixed 100 plate *j* and fixed thereto is a hollow pillar *q*.

The bottom of the box *a*, the edge of which is flared at *r* for a portion of its periphery and is straight for the remainder, is closed by a bottom cover *s* having a 105 flange *t* bent inwards over the flared and straight edges. The cover *s* is embossed at *v*, *v* to form lateral supports for the lock *w*.

of any key-operated type. The lock *w* is provided with a ferrule *x* which may be rolled over to secure it to the cover *s*. The pillar *q* extends to the lock *w* and aids in supporting it. The fixed plate *j* is dished at *y* to allow a coin to be more readily passed under the annular flange *g*. The annular flange *g* and the disc *e* is cut away on its under surface at *z*, *z* to facilitate the insertion of a coin. The box *a* is provided at its straight bottom edge with a slot 2 which is covered by the flange *t*. The bolt of the lock *w* enters the slot 2. The distance between the shoulders 3, 3 of the annular projection *e* of the top *b* is small enough to support the smallest coin in use when the box *a* is upside down so that the finger *m* will lie underneath the coin when the box is in such position and prevent it passing under the finger and being carried round with the disc *e* and falling out of the box when the disc is revolved.

Distance tongues 4, 4 are stamped out of the plate *j* and turned up as shown in the drawing. A recess 5 is formed around the box *a* to lock the plate *j* in position. The handle *p* is formed in one piece with the disc *e* and passed through a slot 6 in the top *b* of the box *a*. The pillar *q* serves as a receptacle for identification papers, thus keeping them from being damaged by the coins. The annular flange *g* of the disc *e* holds a coin securely against removal after it has been inserted in the coin aperture *d* and the disc partly rotated.

In use, the disc *e* is revolved so that a hole *f* therein is in register with the hole *d* in the top *b* of the box *a*, a coin is placed flatways in the recess formed by the revolving disc *e* and fixed plate *j* underneath. The disc *e* is further revolved and the coin drops into the box *a* through the hole *h* in the plate *j*. Should an attempt be made to coax a coin out of the box *a* by placing it upside down and revolving the disc *e*, the finger *m* slips under the coin and lifts it out of the recess so that it cannot pass between the fixed plate *j* and the top *b* of the box *a* and thence through the hole *d* in the top *b*. Should an attempt be made to revolve the disc *e* in the reverse direction to which it is intended to turn, the roller *n* is forced into the narrowing space between the oval box *a* and the circular disc *e* and so locks the disc.

Instead of the arrangement described, the plate *j* may be provided with tongues to engage slots in the side of the box *a* to se-

cure it in position relative to the hole *d* in the top *b*.

If desired, a hole smaller than the smallest coin it is intended to place in the box *a* may be provided for the insertion of a treasury note or the like after it has been rolled up, the hole being so disposed as to prevent interference or tampering with the mechanism inside the box.

What I claim and desire to secure by Letters Patent is:

1. In money boxes wherein a revoluble disc provided with an aperture and constituting a carrier is capable of being revolved between the top of the box and a fixed plate within the box, said top of the box and fixed plate being perforated to allow coins to pass faceways from outside of the box to within the box but in which the perforations do not register, an annular groove in the under face of the top of the box, an annular projection on the upper face of the revoluble disc adapted to coact with the said annular groove, an annular recess in the under-side of said revoluble plate, a spring finger on the upper side of said fixed plate, said finger lying in the annular groove in the revoluble disc so that no coin can pass from the box through the aperture in the revoluble disc to the aperture in the top of the box.

2. In money boxes wherein a revoluble disc provided with an aperture and constituting a carrier is capable of being revolved between the top of the box and a fixed plate within the box, said top of the box and fixed plate being perforated to allow coins to pass faceways from outside of the box to within the box but in which the perforations do not register, and having a lock on a removable bottom adapted to lock the bottom to the sides of the box, an annular groove in the under face of the top of the box, an annular projection on the upper face of the revoluble disc adapted to coact with the said annular groove, an annular recess in the under-side of the said revoluble plate, a spring finger on the upper side of said fixed plate said finger lying in the annular groove in the revoluble disc so that no coin can pass from the box through the aperture in the revoluble disc to the aperture in the top of the box and a pillar secured to the said plate adapted to rest on the lock and form a receptacle within the box for identification papers.

In testimony whereof I affix my signature.

JOSEPH EDGERLEY PURSER.
